UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A HANGING-LAMP FIXTURE.

SPECIFICATION forming part of Design No. 17,927, dated December 6, 1887.

Application filed September 26, 1887. Serial No. 250,787. Term of patent 7 years.

To all whom it may concern:

Be it known that I, ALBERT PATITZ, of Meriden, in the county of New Haven and State of Connecticut, have invented a new Design for the Ornamentation of Hanging-Lamp Fixtures; and I do hereby declare the following, when taken in connection with accompanying drawings and the letters of reference marked thereon, to be a full, clear, and exact description of the same, and which said drawings constitute part of this specification, and represent, in—

Figure 1, a side view of a crown; Fig. 2, under side view, the center being represented as filled.

This invention relates to a design for the circular portions of the suspending part of the lamp-fixture; and it consists in the configuration and ornamentation of the sides of such circular portions, as shown in the accompanying illustration. These parts are circular in shape, as represented in Fig. 2; but in said Fig. 2 the central portion is represented as filled by an open-work; but this may be omitted, as it constitutes no part of the invention, and as the design relates only to the sides, which are alike in both cases. The outer surface in vertical section is of cyma-

recta shape, as seen in Fig. 1, and the surface is represented as made up of series of narrow 30 tongues with spaces between them springing from the base, the said tongues represented as connected across the said spaces one with another, the upper or tip end of the tongues terminating in an outwardly-turned scallop 35 shape above the connection between the tongues, as shown in the accompanying illustration, Figs. 1 and 2.

I claim—

The herein-described design for the ornamentation of the circular parts of a hanging-lamp fixture, the said circular parts consisting of the representation of a series of tongues springing from a base, said tongues presenting a cyma-recta shape in vertical section and with 45 spaces between them, the said tongues represented as connected across between the said spaces, and the tongues represented as terminating in an outwardly-turned scallop shape above the connections, as shown in the accompanying illustration.

ALBERT PATITZ.
